UNITED STATES PATENT OFFICE.

JOHN P. HAYES, OF PHILADELPHIA, PENNSYLVANIA.

HYDROCARBON DEVICE FOR BURNING OFF PAINT.

SPECIFICATION forming part of Letters Patent No. 427,474, dated May 6, 1890.

Application filed July 21, 1886. Serial No. 208,688. (No model.)

To all whom it may concern:

Be it known that I, JOHN P. HAYES, a citizen of the United States, residing at Philadelphia, in the county of Philadelphia and State 5 of Pennsylvania, have invented certain new and useful Improvements in Hydrocarbon Devices for Burning Off Paint, of which the following is a specification, reference being had therein to the accompanying drawings, 10 wherein—

Figure 1 is a side elevation of a hydrocarbon breamer for burning off paint embodying my invention. Fig. 2 is a like view with the shield or tube for the burner removed. Fig. 15 3 is a cross-section of the shield on line 1 1, Fig. 1; and Fig. 4 is a central longitudinal section of the burner drawn to an enlarged scale.

My invention has relation to hydrocarbon 20 breamers for painters' use; and it has for its object simplicity of construction and arrangement of parts for increasing the efficiency and durability of the breamer and to adapt it to be handled for any length of time with ease 25 and without unnecessarily tiring the wrist of the person using it.

My invention accordingly consists of the combination, construction, and arrangement of parts, as hereinafter described and claimed. 30 In the drawings, A represents the oil-reservoir, provided with an oil-tube B, having cut-off b. The latter leads out of the reservoir near the rear side of the same and extends above and across the reservoir, at which part 35 it is provided with a wooden sleeve or handle b'. This pipe or tube B terminates in a vapor-burner C, between which and the tube B and suitably located upon the latter adjacent to the burner is a cup or disk D, for the reception of oil, which is ignited to start the initial vaporization of oil for the burner, as is usual 40 in hydrocarbon-burners of the form described.

The burner consists of a triangular frame, as shown, the base c of which aligns, or approximately aligns, with the end b² of tube B, and is preferably vertically located, as illustrated, and has a central jet or flame opening c', which is closed and opened by suitably adjusting the needle-valve c². The long sides 45 50 c³ c³ of the burner-frame are in front of the base c. The passage-way through the retort-

frame c³ c³ is by way of vertical passage d, leading from pipe B part way up the base c of said frame, which passage or channel d communicates with the passage-ways or channels d' in the sides c³, and thence, by way of the passage-way or channel d² in the upper part of the base c, to the plug and jet-openings. The channels d' and channel d² communicate with openings d³ d⁴, respectively, at 60 the apex of the sides c³ c³ and at the top of the base c, which openings are closed by screw or other removable plugs e, which are provided for gaining access to channels d' d², for inserting the usual rod or other packing in 65 said channels and for cleansing or for other desired purposes.

The triangular form of retort described provides two long sides c³ c³ in front of the jet-tube c, which connects the bases of the 70 sides c³ c³, and they are heated by the flame to vaporize the oil therein. Thus the sides c³ c³ form the retort in which the oil is vaporized. As this retort is in advance of the jet-tube, the full benefit of the heat from the jet or 75 flame is obtained for generating a quick and constant supply of gas or vaporized oil for the burner.

The burner C is surrounded or inclosed in a shield or tube F, which is open at both ends, 80 as shown more plainly by dotted lines, Fig. 2, and is loosely but firmly held upon the burner by means of the shouldered pins g, projecting from the sides of the base c, passing through openings f in the tube or shield 85 at or near its rear end, and by resting at its front end upon the pins g', projecting from the apex of the sides c³ c³. (Shown more plainly in Fig. 3.) The pins g' are preferably used, so as not to obstruct the passage of the 90 flame from or through the tube or shield, and the latter being open at its rear end the necessary supply of air for the jet or flame is provided. The pins g' are of such length and the openings f in the tube are of such diameter that the tube is attachable to and detachable from said pins by springing the openings onto and off of said pins. The tapering plug c² has the usual jam-nut h, if desired, or it may be otherwise constructed, as deemed 95 100 essential.

A paint-burning device constructed as

above described, it will be noted, is of a compact form and can be easily manipulated to accomplish speedy results. The retort is in advance of the jet or flame, and is therefore subjected to the intense heat of the flame to maintain the vaporization of the oil, and at the same time the retort is of such shape that it does not interfere with or obstruct the flame in accomplishing the work desired.

10 By providing the tortuous or triangularly arranged channels d' d^2 , for the passage of the oil and vapors before reaching the jet-opening c' , the oil is thoroughly vaporized before it arrives at the jet or flame.

15 In practice the reservoir A is provided with the usual or desired form of pump a , with or without an air-cock a' , for the customary purposes.

In some cases, if desired, the petcock a' may 20 be dispensed with.

In using the term "hydrocarbon oil" I do not limit myself to any particular grade. It may include gasoline, naphtha, or other suitable material.

25 The arrangement of the handle b' directly over the oil-reservoir brings the weight of the latter in line with the handle, and such weight does not strain or tire the wrist of the person handling the implement, as is the case when 30 the handle is to one side of the reservoir.

What I claim is—

1. In a breamer, the combination of a fluid-reservoir, a pipe B, having a vertical section depending into the reservoir at the outer end 35 of its longitudinal central line and a hori-

zontal section extending across the top of and beyond the opposite end of the reservoir, a burner C at the free end of said horizontal section of pipe B, and a handle on said horizontal pipe-section between said burner and the vertical pipe-section, said handle extending partly across the top of the reservoir and beyond it toward the burner, whereby the weight of the breamer is balanced for use, substantially as set forth.

2. In a breamer, the combination of a burner C, consisting of a base c , having passages d d^2 , opening c' , screw-plug c^2 , and sides c^3 c^4 , tapering from the ends of the base toward a common point and having passages d' d^2 , connected together at one end and respectively communicating with passages d and d^2 at the other end, outside shouldered pins g at the base of said burner, other pins g' at the tapering end of the burner, and a tubular shield F, having openings f , sprung upon the shouldered pins g , substantially as set forth.

3. The burner C, having at one end shouldered pins g and at the other end pins g' , in combination with a shield or tube F, having side openings f , sprung upon shouldered pins g , substantially as and for the purpose set forth.

In testimony whereof I affix my signature in presence of two witnesses.

JOHN P. HAYES.
